UNITED STATES PATENT OFFICE

167,275

PENDANT CROSS

Ennis Rickspoone, New York, N. Y.

Application February 7, 1951, Serial No. 14,124

Term of patent 14 years

(Cl. D45—17)

To all whom it may concern:

Be it known that I, Ennis Rickspoone, a citizen of the United States, residing at New York, in the county of New York and State of New York, have invented a new, original, and ornamental Design for a Pendant Cross, of which the following is a specification, reference being had to the accompanying drawing, forming part thereof.

Fig. 1 is a front elevational view of a pendant cross showing my new design, the back of the cross being the same in appearance as the front; and

Fig. 2 is a side view thereof.

I claim:

The ornamental design for a pendant cross, as shown and described.

ENNIS RICKSPOONE.
